PHOTOMETRIC INSTRUMENT

James H. Casterlin, Binghamton, N.Y., assignor to Koll-morgen Corporation, Holyoke, Mass., a corporation of New York

Filed May 16, 1969, Ser. No. 17,180

Term of patent 7 years

Int. Cl. D10—11

U.S. Cl. D61—1

FIG. 1

FIG. 2

FIG. 3

FIG. 4

FIG. 6

FIG. 5

FIG. 1 is a perspective view of a photometric instrument, showing my new design;

FIG. 2 is a front elevational view thereof;

FIG. 3 is a top view thereof;

FIG. 4 is a rear elevational view thereof; and

FIGS. 5 and 6 are side elevational views thereof.

I claim:

The ornamental design for a photometric instrument, substantially as shown.
